UNITED STATES PATENT OFFICE.

WILLIAM L. POWELL, OF ROANOKE, VIRGINIA.

DESIGN FOR A CLAMP FOR BED-COVERS.

48,125.

Specification for Design.

Patented Nov. 9, 1915.

Application filed March 29, 1915. Serial No. 17,934. Term of patent 7 years.

To all whom it may concern:

Be it known that I, WILLIAM L. POWELL, a citizen of the United States, residing at Roanoke, in the county of Roanoke and State of Virginia, have invented a new, original, and ornamental Design for Clamps for Bed-Covers, of which the following is a specification, reference being had to the accompanying drawing, forming part thereof.

The figure of the drawing is a perspective view showing my new design of cover clamp.

I claim:

The ornamental design for a clamp for bed covers as shown.

WILLIAM L. POWELL.

Witnesses:

NELLIE K. POWELL,
ROY K. BROWN.
